CLAIM

The ornamental design for an archery bow dampener and stabilizer, as shown and described.

DESCRIPTION

FIG. 1 is a perspective view of an archery bow dampener and stabilizer, showing our new design;

FIG. 2 is a front elevational view thereof, the rear being a mirror image thereof;

FIG. 3 is a top plan view thereof;

FIG. 4 is a bottom plan view thereof;

FIG. 5 is a left-side elevational view thereof; and,

FIG. 6 is a right-side elevational view thereof.
